CLAIM

The ornamental design for a raisable plow hitch assembly, substantially as shown and described.

DESCRIPTION

FIG. 1 is a top plan view of a raisable plow hitch assembly showing our new design;

FIG. 2 is a bottom plan view thereof;

FIG. 3 is a sectional view taken in the direction of the arrows along line 3—3 in FIG. 1;

FIG. 4 is a side elevational view thereof;

FIG. 5 is a rear elevational view thereof;

FIG. 6 is a front elevational view thereof.
